UNITED STATES PATENT OFFICE.

CHRISTOPHER ROBERT WILSON, OF PHILADELPHIA, PENNSYLVANIA.

AEROPLANE.

1,345,726.

Specification of Letters Patent.

Patented July 6, 1920.

Application filed April 9, 1919. Serial No. 288,824.

To all whom it may concern:

Be it known that I, CHRISTOPHER R. WILSON, a citizen of the United States, residing at Philadelphia, in the county of Philadelphia and State of Pennsylvania, have invented certain new and useful Improvements in Aeroplanes, of which the following is a specification.

This invention relates to improvements in aeroplanes and more particularly to that type provided with a helicopter adapted to act not only as a safety device in landing but also to aid in leaving the ground and to a certain extent provide for hovering.

One of the objects of the present invention is to provide an attachment for aeroplanes of the above general character having relatively few parts which may be inexpensively manufactured and installed.

A further object is to provide a device of the above character which may be easily controlled and thrown into and out of action as desired and will to a certain extent be automatic in its operation especially when acting as a safety device in landing.

A further object is to provide a reliable and efficient device of the above character which will materially aid in the initial launching of the aeroplane, as well as to permit hovering of the aeroplane above a predetermined object.

Other objects will be in part obvious and in part hereinafter pointed out.

In order that a clearer perception of the present invention may be obtained a drawing depicting a preferred form of the invention is herewith incorporated to form part of this specification and in the several views like reference numerals denote corresponding parts.

In this drawing Figure 1 is a semi-diagrammatic plan view of a portion of an aeroplane with the attachment applied thereto; Fig. 2 is a side elevational view, partly in section, showing the device in operating position, and Fig. 3 is a detail perspective view.

Referring now to the drawings in detail 5 denotes a source of power or engine provided with a shaft 6 and propeller 7. A portion of a wing is indicated at 8 with the attachment centrally disposed in an opening therein. The wing may be of any desired shape, and while herein shown the attachment is centrally applied with respect to the machine it is of course to be understood that

where the fuselage might interfere with the proper operation or installation of the device it might be advisable to install two attachments—one at each side of the fuselage. While this is of course a matter of desirability it is believed to be unnecessary to show such an arrangement in detail.

This attachment comprises a frame-work 10 having a central strut 11 and a depending transverse strut 12, together forming a bearing for a two part shaft 13 centrally disposed thereon. The lower part of this shaft is provided with a pinion 14 adapted to mesh with a pinion 15 carried on a stub shaft 16. This shaft 16, as well as the main shaft 6, is provided with intermeshing gears 17 whereby power is transmitted from the shaft 6 to the shaft 13.

Above the shaft 13 is the second shaft 18 adapted to be driven from the shaft 13 on throwing in a clutch 20. The shaft 18 is provided at its upper end with ball governors 21 connected by means of adjustable links 22 with a sleeve 23 shown in detail in Fig. 3. This sleeve is provided with notches 24 on the sides of which are racks 25 adapted to coat with pinions 26 on propeller blades 27. These blades are mounted in a suitable bracket 28 and on rotation of the pinions 26 the propeller blades will feather in the proper direction to exert or retard air currents either upwardly or downwardly as desired.

It will of course be understood that the clutch 20 is actuated by any suitable form of mechanism such as indicated by the lever 30. This lever has its end connected with other mechanism, not shown, as may be necessary to be conveniently operated by the pilot.

The operation of this mechanism is substantially as follows: On starting the aeroplane the lever 30 is actuated to throw the clutch into engagement, thereby to rotate the propeller 27. The speed with which this is rotated will of course affect the governors 21, and thereby automatically feather the propellers to get the maximum downward pressure of air through the wing. This will aid materially in lifting the machine from the ground. Conversely when the machine is about to land if the engine is going too fast this same downward pressure of air may be utilized to cushion the fall and thereby prevent damage to the machine. If, however, the engine is going

slowly the propellers will be feathered in the opposite direction.

While the machine is in flight the clutch may be thrown in at any time if so desired and the propellers will act to direct the strong downward current downwardly, thereby allowing the machine to hover or remain more or less stationarily suspended in air.

10 From the above it will be seen that the present invention provides a simple and practical attachment for aeroplanes adapted to accomplish, among others, all of the objects and advantages herein set forth.

15 I realize that considerable variation is possible in the details of construction and arrangement of parts without departing from the spirit of my invention, and I therefore do not intend to limit myself to the specific form shown and described.

20 I claim:

1. In combination with an aeroplane having a stationary wing supporting surface, a source of power, a main driving shaft and a driving propeller thereon, of an attachment for said stationary wing supporting surface mounted in an opening formed in said surface, said attachment comprising a propeller mounted for rotation in the plane 25 of the wing supporting surface, a shaft carrying said propeller, means connecting said shaft to said main driving shaft and means for feathering the blades of said propeller automatically in proportion to the speed of the source of power.

2. In combination with an aeroplane having a stationary wing supporting surface, a source of power, a main driving shaft and a driving propeller thereon, of an attachment 30 for said stationary wing supporting surface mounted in an opening formed in said surface, said attachment comprising a propeller for rotation in the plane of the wing supporting surface, a two part shaft, one of which carries the said last mentioned propeller and one of which is connected with said main driving shaft at will, and means 35 for feathering the blade of said last-men-

tioned propeller automatically in proportion to the speed of the main source of power.

3. In combination with an aeroplane having a stationary wing supporting surface, a source of power, a main driving shaft and a driving propeller thereon, of an attachment 40 for said stationary wing supporting surface mounted in an opening formed in said surface, said attachment comprising a propeller mounted for rotation in the plane of the wing supporting surface, a two part shaft, one of which carries said last mentioned propeller, and one of which is connected with said main driving shaft at will, and means for feathering the blades of said last mentioned propeller according to the speed of the main source of power, said means comprising an automatically actuating governor.

4. In combination with an aeroplane having a stationary wing supporting surface, a source of power, a main driving shaft and a driving propeller thereon, of an attachment 45 for said stationary wing supporting surface mounted in an opening formed in said surface, said attachment comprising a propeller mounted for rotation in the plane of the wing supporting surface, a shaft upon which said last-mentioned propeller is mounted, a second shaft adapted to be connected to said last-mentioned shaft and driven from the main driving shaft, a clutch forming said connecting means adapted to be manually operated at will, and an automatically acting governor mounted on said last-named propeller-carrying shaft, and a rack-equipped sleeve connected for vertical movement with said propeller and coacting with pinions on the propeller blades to automatically feather the same in proportion to the speed of the main source of power.

In testimony whereof I affix my signature in the presence of two witnesses.

CHRISTOPHER ROBERT WILSON.
